SLIDE CARRIER

Robert W. French, Jr., Howell, Mich., assignor to
Argus, Inc., Ann Arbor, Mich., a corporation of
Michigan

Application November 1, 1946, Serial No. 707,249

11 Claims. (Cl. 88—28)

1

This invention relates to rotary slide carriers for picture projectors and is particularly concerned with means for at least partially ejecting a picture slide after it has been moved from projection position so that it may be easily grasped by the operator and removed from the carrier.

In its preferred embodiment, this invention will be described as an improvement over the rotary slide carrier illustrated and described in Fassin Patent No. 2,364,627, issued December 12, 1944. Essentially, the Fassin slide carrier has been improved to the extent of adding thereto a slide ejector mechanism operable when the slide carrier has been rotated to move the slide away from its lower projection position into its upper position for removal by the operator.

While slide ejectors for partially ejecting a slide from the carrier have been proposed for reciprocable slide carriers and found generally satisfactory in such carriers, to my knowledge this is the first time that such a slide ejector has been provided for a rotary slide carrier.

It is therefore a major object of my invention to provide a rotary slide carrier having novel means for partially ejecting a picture slide to a position where it may be readily grasped for removal by the operator of the projection machine.

It is a further object of my invention to provide a novel cam slide ejector for a rotary slide carrier for a picture projection machine.

Further objects of my invention will presently appear as the description proceeds in connection with the appended claims and the annexed drawings, wherein:

Figure 1 is a front elevation of a rotary slide carrier according to a preferred embodiment of my invention, particularly showing the shoe for mounting the carrier in the projector;

Figure 2 is a front end view of the carrier of Figure 1 in projection position, further illustrating the cam for ejecting the slide;

Figure 3 is a front elevation similar to Figure 2 but showing the carrier rotated clockwise 90° from projection position and illustrating one slide in dot-dash lines as partially ejected from the carrier;

Figure 4 is a top plan view of the slide carrier of Figures 1 and 2;

Figure 5 is a section along line 5—5 of Figure 2, illustrating a preferred manner of assembly of the cam with the slide carrier;

Figure 6 is a section substantially along line 6—6 of Figure 1 illustrating further the assembly of the cam with the slide carrier;

Figure 7 is an exploded view, mainly in section, of the pivot and cam assembly for mounting

2

the slide carrier and the shoe in assembled relationship;

Figure 8 is an end elevation of the top of the shoe; and

Figure 9 is a section along line 9—9 of Figure 7 illustrating the spindle shape.

My slide carrier comprises essentially a thin metal or like circular plate or disc 11 mounted for rotation about its center upon a shoe or socket 12 that is adapted to interfit with a corresponding support on a part of a projector as disclosed in said Fassin patent.

Socket 12 is preferably made from an integral blank of relatively stiff sheet metal formed with a rectangular picture framing window 13 located equidistantly between forwardly and inwardly bent side walls 14 and 15 which form opposed guide channels spaced to embrace and snugly interfit with a suitable stationary support on the projector as above described. Above window 13, socket 12 is formed with a rounded integral projection 16. At its lower end projection 16 is flanked by forwardly bent integral tabs 17 and 18 arranged at the same level and having flat under-surfaces adapted to rest on the top wall of a suitable support on the projector. Tabs 17 and 18 are so spaced vertically with respect to window 13 that they support and locate socket member 12 on the projector with window 13 optically centered with the projection axis and the lens tube of the projector. Channels 14 and 15 locate window 13 horizontally centrally in the projection light path and so interfit with the support on the projector that shoe 12 is non-rotatably mounted on the projector. Thus shoe 12 provides a non-rotatable but removable support for my rotary slide carrier on the projector. This shoe is substantially the same as the shoe disclosed in Fassin Patent 2,364,627 and is preferably associated with the projector in the same manner as in that patent.

Above window 13 and vertically aligned with the optical center of window 13, projection 16 is substantially centrally provided with a relatively small circular aperture 19 (Figure 7) in which is secured a short hollow rigid cylindrical hub member 21 that has its reduced forward end 22 staked over or otherwise rigidly secured within aperture 19 so as to secure hub 21 non-rotatably to socket 12. If desired, hub 21 could be made integral with projection 16. Hub 21 is internally provided with a cylindrical bore 23 and a smaller partly cylindrical and partly flat-sided bore 24, illustrated best in Figure 8, which provides a flat radial shoulder 25 within hub 21.

Carrier plate 11 has secured thereto on the side opposite shoe 12 a pair of channel forming strips 20 that internally contain springs 20' for resiliently and frictionally holding the slides in inserted position. These springs, which are preferably the same as those fully illustrated and described in said Fassin patent, serve as stops to locate slides S₁ and S₂ in position before the associated apertures 40 and 41 of plate 11.

A short spindle 26 is formed successively with a cylindrical portion 27 and a partly cylindrical and partly flat-sided portion 28 adapted to interfit snugly with bore 24 so that in the assembly the spindle will be non-rotatable but slidably axially with respect to hub 21. Portion 28 is longer than bore 24 in the axial direction to permit axial sliding of spindle 26 during turning of carrier 11. At its forward end spindle 26 is formed with a short cylindrical portion 29 which is reduced in size to interfit frictionally with a circular aperture 31 in the center of plate 11. The axial length of portion 29 equals the thickness of plate 11. Spindle 26 terminates in a screw threaded end portion 32 that extends through a suitable spacing washer 33 and a slide ejector cam 34 into a nut 35 which, when drawn tight, holds the spindle, shoe and disc assembly together. Within bore 23, a coiled compression spring 36 surrounds the shank of spindle 26, and spindle 26 is formed with a large cylindrical head which is of only slightly less diameter than the diameter of bore 23 so as to slidably fit therein. When nut 35 is tight, head 37 compresses spring 36 and is positioned within bore 23 so as to close the outer end of bore 23.

Preferably, cam 34 is a cylindrical metal block which is eccentrically formed with a threaded aperture 38, whereby the cam may be mounted on threaded portion 32 of the spindle 26 like a nut. The function of washer 33 is to provide an anti-friction axial thrust bearing connection between cam 34 and plate 11 when plate 11 is rotated about the journal provided by cylindrical portion 29 of spindle 26. When nut 35 is drawn tight, the spindle 26 is non-rotatably but axially slidably coupled to shoe 12, spring 36 controlling axial displacement of the spindle.

With spindle 26 and spring 36 inserted through bore 23 as illustrated in Figure 6, and with the cam 34 mounted on the spindle and locked tight thereon by nut 35, cam 34 is rigid with spindle 36 which in turn is non-rotatable with shoe 12 and the projector supporting it. Care must be taken that cam 34 is so mounted upon spindle 26 that it is oriented in the generally horizontally extending position illustrated in Figures 2 and 3, whereby when disc 11 is turned clockwise so as to move its lower projection aperture 40 through 180° to the upper slide insertion and removal position indicated at aperture 41, the slide will be partially ejected by the action of the cam.

Cam 34 in the illustrated embodiment is disposed with its major axis of eccentricity at 90° to the vertical. The size and eccentricity of cam 34 is determined by the distance that it is desired to eject the slide. The cam must be so dimensioned and shaped that it will not interfere with full insertion of a slide into the dotted line position S₂ illustrated at the top of Figure 2. This is the slide insertion and removal station. After inserting a slide before aperture 41, plate 11 is turned 180° in the direction of the arrow indicators 42-43, which is clockwise, to position slide S₂ before the window 13; that is, the position S₁ at the bottom of Figure 2.

During the 180° movement just described, cam

34 of course has no action on the slide. After the slide at S₁ has been projected, carrier 11 is then rotated another 180°, a fresh slide having been inserted at the top of S₂ in the meantime, so as to bring the slide S₁ to the top position where it may be withdrawn from the carrier. During its upward movement to the slide extracting position, the bottom edge of slide S₁ is engaged by the projecting eccentric portion of relatively stationary cam 34 which thereby forces the slide radially outwardly in its guide substantially into the dot-dash line illustrated at Figure 3. The eccentricity of cam 34 determines the amount that the slide is ejected and preferably the full throw of the cam, or maximum ejection, is accomplished by the time that the carrier has rotated to the 90° position illustrated at Figure 3. Rotation of the carrier plate 11 continues until slide S₂ assumes the position formerly held by S₁ in Figure 2, but with the difference that the slide S₁ now projects an appreciable distance above the rim of plate 11 and is readily available to be grasped by the fingers of the operator and extracted without danger of injury to the picture or other portions of the slide. The slide is frictionally held in partially ejected position by the action of the springs in the guide, which normally tend to hold the slide in any radial position.

While cam 34 is illustrated as a solid block in Figures 1 through 9, it may assume any suitable form; for example, it may be a cylindrical cup-shaped hollow stamping of steel metal, or it may simply comprise any part eccentric from the axis of spindle 26 which will engage the bottom edge of slide S₁ and force it outwardly a desired distance during rotation of plate 11 to bring S₁ from the lower projection position to the upper extraction position. In practice the throw of a suitable cam 34, using 2"-by-2" conventional color transparency slide mounts as S₁ and S₂, is satisfied by a horizontal eccentricity of about $\frac{1}{4}$ inch in the cam.

During rotation of disc 11 relative to shoe 12, cooperating detents and apertures on the shoe and disc serve to locate disc 11 in either of its two 180° apart projection positions, axial separation of the shoe and disc as the detents ride between the apertures being permitted by the axial sliding between spindle 26 and hub 21 against the force of spring 36, all as disclosed in said Fassin patent.

The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. In a rotary slide carrier, a stationary support, a slide mounting member rotatable about an axis on said support, a spindle non-rotatably mounted on said support and on which said rotatable member is journaled, and a radially extending projection on said spindle adapted to engage and partially eject a slide from said movable member as the latter rotates away from slide projecting position.

2. In the carrier defined in claim 1, said spindle being axially slidably supported on said support.

3. In the carrier defined in claim 1, said projection comprising an eccentric cam rigid with said spindle.

4. In a rotary slide carrier assembly, a stationary hub, a spindle non-rotatably but slidably mounted within said hub, a slide carrying member rotatably mounted on said spindle, and a radially projecting slide engaging and ejecting member rigid with said spindle.

5. In a rotary slide carrier having a support for mounting it on a projector, a slide mounting member rotatably mounted on said support and turnable through more than a single revolution in a given direction, a substantially radial slide socket on said member and means stationary with said support adapted to engage and outwardly displace a slide in said guide to partially eject a slide from said member during rotation of said member to move a slide away from projection position.

6. In a rotary slide carrier, a support having a bore, a longitudinally biased spindle axially slidable in said bore but non-rotatable with respect to said support, a cylindrical portion on said spindle, a rotatable slide mounting member journaled on said cylindrical portion, and a slide ejector on said spindle having a radially projecting part adapted to engage and partially eject a slide from said member during rotation of said member.

7. In a rotary slide carrier assembly, a stationary spindle, a picture slide mount member journaled on said spindle, guide means on said member for slidably receiving a picture slide and a radial projection on said spindle for engaging the inner edge of a picture slide in said guide means and partially ejecting the picture slide during rotation of said member.

8. In the assembly defined in claim 7, said guide means extending radially of said spindle.

9. In a rotary slide carrier, a member having a part for attachment to a projector, a slide support mounted on said member for rotation about an axis for successively moving said slide support from an initial position where a slide may be placed on said support to a slide projection

position and then back to said initial position, said support being rotated about said axis in the same direction to accomplish said successive movements, and relatively stationary means on said member effective only during rotation of said support to engage and displace said slide substantially radially outwardly of said support for partially ejecting said slide from said support so that the slide may be readily available for extraction from said support by an operator.

10. In a rotary slide carrier assembly, a support having a part for attachment to a projector, a member on said support rotatable through more than a single revolution in a given direction for successively carrying a slide into and out of projection position, and relatively stationary means on said support projecting eccentrically with respect to the axis of rotation of said member for engaging and displacing said slide substantially radially outwardly of said member for partially ejecting said slide from said member as the latter rotates away from said projection position.

11. In a rotary slide carrier assembly, a support having a part for attachment to a projector, a slide mounting member on said support rotatable through more than a complete revolution in a given direction, a radial slide socket on said member and relatively stationary means on said support offset with respect to the axis of rotation of said socket adapted to engage and partially eject a slide from said member as said member is rotated away from slide projecting position.
